TAPE DISPENSER OR THE LIKE

Theodore H. Krueger, Strafford, Conn.
(% Better Packages, Inc., Shelton, Conn.)

Filed June 10, 1959, Ser. No. 56,296

Term of patent 14 years

(Cl. D74—1)

Fig. 1 is a perspective view of a tape dispenser, showing my new design;

Fig. 2 is a side elevation of the control housing or key drum of the dispenser shown in Figure 1;

Fig 3 is a front elevation of the control housing or key drum shown in Fig. 1;

Fig. 4 is a rear elevation of the same.

The dominant features of my design reside in the portions shown in full lines.

I claim:

The ornamental design for a tape dispenser or the like, as shown and described.
